WATCH BAND

Earl R. Wright, Comanche, Tex.

Application March 25, 1950, Serial No. 8,764

Term of patent 7 years

(Cl. D45—4)

To all whom it may concern:

Be it known that I, Earl R. Wright, a citizen of the United States of America, residing at Comanche, in the county of Comanche and State of Texas, have invented a new, original, and ornamental Design for a Watch Band, of which the following is a specification, reference being had to the accompanying drawing, forming a part thereof.

The figure is a top plan view of the watch band, which band is of no substantial thickness.

I claim:

The ornamental design for a watch band, substantially as shown and described.

EARL R. WRIGHT.
